George B. Foster, of Boston, Mass:
Letters Patent No. 943. Dated Sept 22. 1857.

The schedule referred to in these Letters Patent, and making part of the same.

To all Persons to whom these Presents shall come:

Be it known that I, George B. Foster, of Boston, in the County of Suffolk, and State of Massachusetts, have produced a new and original design for an ornamental shade for gas burners, &c. And I do hereby declare that the said new design is fully described and represented in the following specification and accompanying drawings, to which reference is herein after made.

The figures of the accompanying plate of drawings represent my new design.

Fig: 1. is an elevation of a glass or porcelain shade such as is used for gas burners with my new design applied thereto.

Fig: 2. is a central vertical section of the same.

My new design consists of an ornamental circular rim of metal or other proper material secured to the top and bottom of the shade, a, a, in the drawings represent the shade made of glass or porcelain. On both the top and bottom of this shade is secured a circular rim b, b, ornamented with leaves, c, c, &c. scrolls d, and raised circular figures, e, e.

Having thus described my new design, I shall state my claim as follows:

What I claim as my invention or production and desire to have secured to me by Letters Patent, is the new design for shades for gas burners &c, which consists of the circular rims or borders ornamented as herein described and represented in the drawings.
